UNITED STATES PATENT OFFICE.

FRANK GODLEWSKI, OF ST. LOUIS, MISSOURI.

DOOR LOCK.

Application filed March 24, 1922. Serial No. 546,323.

To all whom it may concern:

Be it known that I, FRANK GODLEWSKI, a citizen of the United States, residing at St. Louis, in the county of St. Louis and State 5 of Missouri, have invented certain new and useful Improvements in Door Locks, of which the following is a specification.

This invention relates to locks, having more particular reference to a lock intended 10 for use on the doors of houses, apartments, or buildings generally.

The invention has for an object to provide a novel and improved lock of this type, which combines the features of simplicity 15 of construction and difficulty in picking.

For further comprehension of the invention, and of the objects and advantages thereof, reference will be had to the following description and accompanying drawings, 20 and to the appended claims in which the various novel features of the invention are more particularly set forth.

Fig. 1 of the drawings is a face view of a lock constructed according to my invention, showing it in place on a door.

Fig. 2 is a face view of the lock alone with one face plate removed, this view being taken looking in the opposite direction to Fig. 1.

Fig. 3 is a transverse vertical sectional view taken on the line 3—3 of Fig. 2.

Fig. 4 is a horizontal sectional view of the lock, removed from the door, this view being taken on the line 4—4 of Fig. 2.

Fig. 5 is a detail perspective view of the key.

Referring now to the drawings my improved lock comprises a casing of the rectangular shape common to door locks and comprising the opposed face plates 10 and 11 which are each provided with two flanged edges 10' and 11' which unite to form the edge walls of the lock. In use, the lock is mounted on the inner face of the door, indicated at 12, with the plate 11 against the door, the two plates being held together on the door by means of screws 13 passing therethrough and into the door.

Within the lock casing a bolt 15 is slidably mounted, and has a diminished end 15' which projects through a suitable opening 16 in one of the flanges 10' and is adapted to engage in the usual keeper of the door frame 17. This bolt end 15' is beveled on one face in the usual manner as at 18. To guide the bolt 15 in its movement, a stud 20

is fixed to the plate 10 and engages in a longitudinal slot 21 in the bolt. Fixed in the inner end of the bolt, and projecting through a horizontal slot 22 in the plate 10, 60 is a stud 23 having a knob or head 24 on its projecting end whereby the bolt may be retracted by hand, this slot 22 having at its rear end an upward offset 25. The bolt 15 is urged forward by a bow spring 28 connected at one end to a stud 29 on the plate 10 and having its other end engaging in a notch 30 in the rear end of the bolt. It will be noted that the disposition of the spring 28 is such that it tends to press the bolt both forwardly and upwardly so that when the bolt is retracted to bring the stud 23 in registry with the offset 25 in the slot 22, the rear end of the bolt will be thrown upward to cause the stud to engage in this offset and so retain the bolt in its retracted position. The parts, also, are so proportioned that stud 20 is at this time at the forward end of slot 21 in the bolt so that the latter pivots on said stud, the opening 16 70 in the flange 10 being vertically elongated 75 to allow the bolt end 15' to swing.

To receive the key, the plate 11 is formed with a hollow boss 33 which extends through the door 12, the latter having upon its outer face a scutcheon plate 34 secured by screws 35, and formed with a circular opening of similar size to the opening 36 through boss 33. The key is shown in detail in Fig. 5 and comprises a shank 38 to the forward end of which is pivoted as at 39 a bit 40. When the key is inserted into the lock the bit 40 extends in alinement with the shank 38 as shown in Fig. 5, being thrown to the operative position extending at right angles to the shank as indicated in dotted lines in Fig. 3 after insertion in the lock. The bit is yieldingly held in either position by means of a spring 41 in the shank 38 which engages the squared rear end of the bit in 95 the manner usual with clasp knives.

The bit 40 when in its angular position is disposed in front of a lug 43 projecting from the bolt 15, which lug it engages to retract the bolt when the key is turned. To 105 cause the bit 40 to be moved to its angular position when inserted in the lock the plate 10 is formed with a vertical slot 44 whose lower end is juxtaposed to the bore of boss 33. This slot is curved by an outwardly 110 bowed spring 45 secured at one end as at 46 to the plate 10 while the forward end of

the bit is beveled on its underside as at 47. When the key is inserted, this beveled end engages the bowed spring 45 and causes the bit to be turned upwardly to its operative position. Inward movement of the key being limited by engagement of the end of shank 38 in a shallow recess 50 of circular outline in the plate 11 and with which the lower end of slot 44 communicates. The bit is provided with suitable ward notches 48 which register with studs 49 on the face plates of the lock in the manner common to key bits. To permit of the bit swinging to and from its angular position as the key is inserted and withdrawn the inner end of the key opening 36 is flared as at 51.

It is believed that the manner of operation of my improved lock will be readily understood from the above description. To facilitate the insertion of the key with the bit properly positioned to pass into the slot 45 the scutcheon plate 34 is formed at the top with a pointed projection 34'. When the key is inserted, the bit 40 engages the spring 45 and is moved upward, the inward movement of the key continuing until the end of shank 38 engages the plate 10. The key is then partially turned, engaging the lug 43 on bolt 15 and retracting the latter. When the bolt reaches the end of its retracting movement the stud 23 thereon engages in the offset 25 in slot 22 and holds the bolt retracted until it is released by pushing downward on the knob 24. Movement of the bit 40, when the key is being rotated backward is limited by a stud 55 on the plate 10.

Having thus described my invention what I claim as new and desire to protect by Letters Patent of the United States is as follows:

1. In combination, a lock comprising a casing, a bolt slidable therein, an element on said bolt adapted to be engaged by a key-

bit to retract the bolt, a key comprising a shank and a pivoted bit, and means on the casing adapted to engage said bit to move it into operative relation to said element when the key is inserted in the lock, said means comprising a bowed spring carried by the casing.

2. In combination, a lock comprising a casing having opposed face plates, a bolt slideable therein, a lug on said bolt adapted to be engaged by a key-bit to retract the bolt, a hollow boss formed on one of said face plates, the other face plate having a slot registering at one end with the bore of said boss, and a flat spring extending along and covering said slot.

3. In combination, a lock comprising a casing having opposed face plates, a bolt slideable therein, a lug on said bolt adapted to be engaged by a key-bit to retract the bolt, a hollow boss formed on one of said face plates, the other face plate having a slot registering at one end with the bore of said boss, and a flat spring extending along and covering said slot, said spring being outwardly bowed between its ends and being secured at one end only to the casing.

4. In combination, a lock comprising a casing having opposed face plates, a bolt slideable therein, a lug on said bolt adapted to be engaged by a key-bit to retract the bolt, a hollow boss formed on one of said face plates, the other face plate having a slot registering at one end with the bore of said boss, and a flat spring extending along and covering said slot, said spring being outwardly bowed between its ends and being secured at one end only to the casing, and a key having a pivoted bit adapted to be moved by said spring into operative relation to the said lug.

In testimony whereof I have affixed my signature.

FRANK GODLEWSKI.
